UNITED STATES PATENT OFFICE.

EMIL E. BÖRSENBERGER, OF WAYNESBURG, OHIO, ASSIGNOR TO THE WHITACRE-GREER FIREPROOFING COMPANY, OF WAYNESBURG, OHIO, A CORPORATION OF OHIO.

DIE FOR HOLLOW TILE.

Application filed January 8, 1927. Serial No. 159,916.

The invention relates to dies such as are used upon a brick machine or the like, and particularly to a die for forming hollow tile.

- 5 Dies for forming hollow tile comprise a die block provided with an opening corresponding to the cross sectional size and shape of the tile to be formed, a bridge being mounted upon the inner side of the die block and 10 supporting a plurality of cores within the opening, so arranged as to produce the desired size and shape of openings through the hollow tile.

In dies of this character such as are in 15 general use, considerable difficulty is experienced in maintaining a uniform flow of the clay through the entire area of the die.

The objects of the present invention are to provide an arrangement and construction 20 of the bridge by locating the arms thereof directly in line with the spaces between the cores which tends to more evenly and uniformly distribute the flow of clay through the interior portion of the die; to provide 25 adjustable plates around the edge of the die for controlling the flow of clay through the outer portion of the die, and to provide means for controlling the flow of the clay at the intersections of the spaces between the 30 cores, without removing the die from the machine.

An embodiment of the invention is illustrated in the accompanying drawings, in which

35 Figure 1 is a front elevation of a die embodying the invention;

Fig. 2, a rear elevation of the same;

Fig. 3, a transverse section through the die taken substantially on the line 3—3, Fig. 40 2, and

Fig. 4, a detached fragmentary perspective view of a portion of the bridge, showing the means for controlling the flow of clay through an intersection of the spaces between the cores.

Similar numerals of reference indicate corresponding parts throughout the drawings.

50 The die block 1 may be provided with the apertures 2 by means of which it may be connected by bolts or the like to a brick ma-

chine of any approved construction, and has the central rectangular opening 3 which receives the former frame 4, of the proper size and shape to produce the desired tile, and 55 preferably tapered toward the outside as in standard practice.

An integral rim lip 5 may be provided upon the outer side of the die block 1, around the central opening 3, and the usual rectangular frame 6 may be connected thereto as by the 60 bolts 7 and provided with the grooved frame 8, having the lips 9 arranged to form the usual dove-tail grooves in the outer walls of the tile.

The bridge comprises the central longitudinal arm 10 and the transverse arms 11, corresponding in number and location to the partition walls arranged to be formed in the tile by means of the spaces between the 70 cores of the die for the purpose of more evenly and uniformly distributing the flow of clay through the interior portion of the die.

This bridge is arranged to be mounted 75 upon the rear side of the die block by the bolts 12, the spacer tubes 13 surrounding said bolts and being interposed between the arms of the bridge and the flange 14 of the former frame 4, thus connecting both the former frame and bridge to the die block, and holding the parts in proper spaced relation.

Shorter transverse arms 15, corresponding in number to the cores 16, are mounted in 85 oppositely disposed pairs upon the longitudinal central arm 10. Each of these arms is provided with an angular extension 17 disposed toward the die block and carrying a core 16.

Each of the cores 16 may be hollow as illustrated, a screw 18 connecting the same to the end of the corresponding angular extension 17.

The cores 16 are so shaped and arranged as 95 to provide for the proper arrangement of openings through the tile, the longitudinal and transverse spaces 19 and 20 respectively, between said cores providing for the formation of the longitudinal and transverse partition walls within the tile.

For the purpose of controlling the flow of

clay through the die, at the intersections of the longitudinal and transverse spaces 19 and 20, a member 21 is located at each intersection, and may be cross-shaped as illustrated, conforming substantially to the shape of the intersection.

Each of these members may be provided with a squared central aperture 22 adapted to be received on the squared portion of a screw 24, carried by the bridge, a nut 25 being provided upon the screw for adjusting the position of the member 21 toward or from the die block.

In order to control the flow of clay around the edge of the die, a plurality of plates 26 are slidably mounted upon the inner side of the die block adjacent to the central opening therein, and arranged to be adjusted toward or from the cores, in order to reduce or increase the speed of flow at any desired point around the die.

Each plate 26 may be provided with a lug 27, extended into a suitable opening 28, in the inner side of the die block, and provided with a threaded bore 29, which receives the threaded end of the adjusting screw 30.

The adjusting screws may extend through the outer edge of the die block and may be provided with the heads 31, located between the die block and the bracket 32, a squared shank 33 extending beyond the bracket to receive a wrench or other tool for operating the screw.

With the present construction, a straight flow of clay through the die is produced, while in the old type of die the flow of the clay is changed by the devices used for retarding the flow at the fast points.

I claim:

1. A die for making hollow tiles comprising a die block having a central opening, a bridge across said opening upon the inner side of the die block and comprising longitudinal and transverse arms, and spaced cores carried by said bridge and located within said central opening, the legs of said bridge being located directly in line with the spaces between said cores for the purpose of evenly and uniformly distributing the flow of clay through the interior portion of the die.

2. A die for making hollow tiles comprising a die block having a central opening, a bridge across said opening upon the inner side of the die block, spaced cores carried by said bridge and located within said central opening and means for controlling the flow of clay through the intersections of the spaces between the cores, and between said cores and the edge of said central opening without removing the die.

3. A die for making hollow tiles comprising a die block having a central opening, a bridge across said opening upon the inner

side of the die block, spaced cores carried by said bridge and located within said central opening, and means for controlling the flow of clay through the intersections of the spaces between the cores, without removing the die.

4. A die for making hollow tiles comprising a die block having a central opening, a bridge across said opening upon the inner side of the die block, spaced cores carried by said bridge and located within said central opening, and cross-shaped members located directly in rear of the intersections of the spaces between the cores for controlling the flow of clay therethrough.

5. A die for making hollow tiles comprising a die block having a central opening, a bridge across said opening upon the inner side of the die block, spaced cores carried by said bridge and located within said central opening, cross-shaped members located directly in rear of the intersections of the spaces between the cores for controlling the flow of clay therethrough, and means for adjusting the position of said cross-shaped members toward or from the cores.

6. A die for making hollow tiles comprising a die block having a central opening, a bridge across said opening upon the inner side of the die block and comprising longitudinal and transverse arms, spaced cores carried by said bridge and located within said central opening, the arms of the bridge being located directly in line with the spaces between said cores and means upon the intersections of the arms of the bridge for controlling the flow of clay between the cores.

7. A die for making hollow tiles comprising a die block having a central opening, a bridge across said opening upon the inner side of the die block and comprising longitudinal and transverse arms, spaced cores carried by said bridge and located within said central opening, the arms of the bridge being located directly in line with the spaces between said cores and cross-shaped members upon the intersections of the arms of the bridge for controlling the flow of clay between the cores.

8. A die for making hollow tiles comprising a die block having a central opening, a bridge across said opening upon the inner side of the die block and comprising longitudinal and transverse arms, spaced cores carried by said bridge and located within said central opening, the arms of the bridge being located directly in line with the spaces between said cores, cross-shaped members upon the intersections of the arms of the bridge for controlling the flow of clay between the cores and means for adjusting the cross-shaped members toward or from the cores.

9. A die for making hollow tiles comprising

ing a die block having a central opening, a bridge across said opening upon the inner side of the die block, spaced cores carried by said bridge and located within said central opening, and plates slidably mounted at the edge of the central opening for controlling the flow of clay between said cores

and the edge of the central opening and adjusting means for said plates located through the sides of the die block. 10

In testimony that I claim the above, I have hereunto subscribed my name.

EMIL E. BORSENBERGER.
